STOVE

Bertrand B. Kahn, Cincinnati, Ohio, assignor to
The Estate Stove Company, Hamilton, Ohio, a
corporation of Ohio

Application June 1, 1936, Serial No. 82,710

11 Claims. (Cl. 126—339)

This invention relates to stoves, and more particularly to broiler constructions therefor.

The principal object of the invention is to provide a simple and effective broiler construction having a food support adapted to be adjusted in elevation from outside the stove and which is withdrawable and removable from within the stove.

Another object is to provide a broiler construction in which a broiler frame is withdrawably mounted within the broiler compartment and is adjustable as to elevation under the control of mechanism associated with and operable from the exterior of the broiler compartment.

15 A further object is to provide a broiler construction in which a removable broiler frame is adjustable as to elevation within a broiler compartment by means of mechanism fixed to and operable from the exterior of the broiler compartment which automatically disengages from the broiler frame on removal thereof from the compartment and automatically reengages on replacement.

In the drawings, in which a preferred embodiment of the invention is shown,—

25 Fig. 1 is a vertical front section taken on the line 1—1 of Fig. 2;

Fig. 2 is a vertical side section taken on line 2—2 of Fig. 1;

30 Fig. 3 is a side elevational view of the stove, on a reduced scale, and showing the location of the external control of the broiler mechanism;

Fig. 4 is a fragmental horizontal section taken on line 4—4 of Fig. 2; and

35 Fig. 5 is a detailed fragmental vertical section taken on line 5—5 of Fig. 2, and showing on an enlarged scale details of the operating mechanism.

In the accompanying drawings, which illustrate 40 a preferred embodiment of the invention, a stove constructed in accordance with the present invention is indicated generally at 10. Included in this stove is a broiler compartment indicated generally by the numeral 11, having a bottom wall 12, rear wall 13, top wall 14, and side walls 15 and 16, these walls preferably being double as shown with heat insulating material therebetween. Front wall 17 has an opening 18, which is of sufficient size to receive the broiler frame, indicated 45 generally at 20, and associated parts. Closure 19 is provided to close opening 18, and is preferably rigidly attached to broiler frame 20, and movable longitudinally therewith, these parts being so related that closure 19 closes the compartment when frame 20 is in its operative position

within the compartment. A suitable heat source 21 is provided within the upper part of the broiler compartment.

5 Broiler frame 20 provides a base on which the food supporting mechanism is mounted for cooperative relation, at various elevations, with respect to heat source 21. In the embodiment shown, the frame 20 comprises a bottom plate 22 which is formed of sheet metal and provides a surface for collecting any food material that may 10 fall during cooking. The sides of bottom plate 22 terminate in upturned flanges 23, which are preferably formed integrally with the bottom plate 22 and secured at the four corners as by spot welding. These flanges serve to form with bottom 15 plate 22 a tray protecting other parts of the broiler from food particles, and also serve as attaching means for the closure and other associated parts. The rearwardly facing portion of flange 23 is provided with an upstanding reinforcing plate 24, which extends across the entire width of the broiler chassis, and upwardly to a point somewhat below the level of the top of opening 18. Supported from this reinforcing plate 20 24 are side bearing plates or brackets 25, which are located on either side of broiler chassis 20 and extend from the top of reinforcing plate 24 to bottom plate 22, where they are fastened. These bearing plates or brackets 25, are located somewhat inwardly of the side portions of flanges 23, to provide the necessary clearance space for 25 the food supporting mechanism to be described below.

The broiler frame 20 and its associated parts 30 is provided with means for their withdrawal. In the embodiment shown, this is accomplished by the use of two pairs of rollers and a pair of track members. Forward rollers 30 are supported from bottom wall 12 of the broiler compartment by means of brackets 31. These brackets carry 35 bearing pins 32 on which rollers 30 are mounted, and are located at the forward or open end of the broiler compartment, and so placed laterally as to underlie the edges of bottom plate 22 of the broiler frame 20. Movable rollers 33 are mounted 40 on the broiler frame sides, and at the rearward portion thereof, by means of stub shafts 34 fastened at the rearward portion of the sides of flange 23. These rollers engage tracks 35 which are fixedly attached to the side walls of the 45 broiler compartment. It is also apparent that the rollers on the same side of the frame are displaced laterally, thus allowing the broiler frame to be completely withdrawn without the two sets 50 of rollers interfering with each other. Tracks 55

35 extend forwardly to a point adjacent the plane of the front wall 17; thus when reinserting the broiler frame after removal it is a simple matter to place movable rollers 33 into engagement with 5 these tracks.

The foodstuff supporting mechanism comprises a broiler pan support 40 which is supported from the pair of bearing plates 25 in overhanging relationship to bottom plate 22. Broiler pan support 40 comprises a rectangular frame portion, having rearward extensions 41 formed on the sides thereof. It is preferred to form this pan support from a U-shaped strip of sheet metal, the sides of the U forming the side portions 15 and the integral extensions 41, the side portions being joined by cross piece 42, which is preferably inturned at the ends and welded to the side portions of support 40. The rearward ends of extensions 41 carry inwardly facing pins 20 43 which are received in curved slots 44 formed in each of the bearing brackets 25, and thus provide for limiting longitudinal movement of the support while providing for adjusting the elevation thereof. The forward ends of the side 25 pieces of broiler pan support 40 are pivotally connected at 45 to arms 46, which extend downwardly and rearwardly and have their rear portions pivoted at 47 to brackets 25. This construction is such that as the inner end of the 30 support 40 is moved or adjusted to any predetermined elevation, the arms provide for maintaining the entire structure 40 in a substantially horizontal position, and at the elevation determined by the adjustment of the inner end. To 35 insure movement of the structure in this path and the prevention of any twisting, stabilizer cross bar 50 is employed. This bar extends across the entire width of the broiler chassis 20 and is journaled on either side in holes 51 formed in brackets 25, and has its portions outward of these supports forwardly turned at 52. The ends of these forwardly turned portions have projections extending inwardly as shown at 53, and these are received in slots 54 which are formed 40 by depending U-shaped brackets 55 attached to the rearward portions of the side pieces of broiler pan support 40. It will be understood that stabilizer bar 50 serves to maintain both sides of the frame at the same elevation throughout adjusting movements thereof and provides for 45 obtaining a firm and rigid structure which can be fabricated from light weight sheet metal parts.

In order to effect the adjustment in elevation of the broiler pan support from outside the 55 broiler compartment, the member 53, at one side of the frame, is formed with an outwardly projecting portion 57, and a roller 58 is pivotally mounted on this overhanging end. The roller runs within a channel shaped track or guide member 59, positioned adjacent the interior wall of the oven or broiler compartment. The guide is pivotally attached to the oven wall by means located adjacent the forward part of the compartment, the inner end of the guide being free 60 and adapted to occupy different angular positions, at varying elevations. The outer end of the guide, being relatively close to the point of support, maintains substantially the same elevation at all angular positions of the guide within 65 its range of movement.

The pivotal supporting means for the guide includes a reinforcing member 60 fastened into the side wall of the stove, preferably between spaced wall plates thereof, this member having substantial area in contact with the wall plates

to distribute the stresses thereto. A pivot pin 61 passes through the reinforcing member 60 and guide 59, the guide being thereby supported for pivotal adjusting movement over a predetermined range. An intermediate operating element 62 is also mounted on pivot 61 and is attached to the guide so that the two parts pivot together. The operating member 62 is formed with a pair of downwardly extending fingers 63, lying respectively on opposite sides of a vertical 10 axis through pivot 61. A shaft 64 is rotatably mounted within reinforcing member 60, the outer end extending to the exterior of the oven compartment upon which is fastened the manually adjustable knob 65. The inner end of the shaft 15 has fixed thereto an eccentrically formed camming member 66 which is positioned between and in operative engagement with the fingers 63. Thus upon rotation of shaft 64, the eccentric member 66 will be rotated into engagement with 20 one or the other of fingers 63, to cause the pivoting of the entire guide 59 about pivot 61, with resultant adjustment of the elevation of the inner end of the guide. The guide is held in any desired adjusted position as a result of 25 frictional engagement between the parts of the operating mechanism; if desired a yieldable ratcheting means of suitable character may be associated with shaft 64 to additionally provide for retaining the same in any adjusted position. 30 Also suitable indexing means may be associated with operating handle 65 to indicate the position of the broiler pan within the oven.

The operation of the device should be clear from the above description. With the broiler 35 device in its operative position within the compartment, changes in elevation thereof are effected under the control of the externally operable adjusting knob 65. This knob is conveniently positioned adjacent the lower front portion 40 of the oven so that it is readily accessible for the operator. Upon rotation of this knob, camming member 66 engages one or the other of the fingers 63 to cause pivotal movement of guide 59. Such pivotal movement results in 45 either raising or lowering the inner end of the guide, with a corresponding raising or lowering of roller 58. Such motion is transmitted directly to the adjacent projection 53, and by means of the reinforcing bar 50, to the member 53 located upon the opposite side of the frame. Motion of these two members thus results in the raising or lowering of the inner end of the frame support, and adjustment thereof to the desired elevation, and the linkage mechanism previously described provides for adjusting the entire frame structure to a corresponding elevation, the broiler pan support 40 assuming a substantially horizontal position at the desired elevation. 55

When it is desired to withdraw the broiler device, as for instance to obtain access to the broiler pan support, the entire assembly including the front closure 19 is drawn outwardly upon the supporting rollers 30, 33. As a result of such movement, roller 58 travels forwardly in the 60 guide 59, meanwhile effecting the lowering of the broiler pan support from whatever position of adjustment it occupied. In the normal outer position of the device, the roller 58 has traveled along guide 59 to substantially the pivotal axis 65 thereof, at which position the broiler frame is in its lowermost position of adjustment as determined by the vertical length of the slots 44. Thus regardless of the position of adjustment of the elevating mechanism, the broiler pan al- 70 75

ways assumes its lowermost position of adjustment when the drawer is fully open. And in this position, if desired, the entire assembly may be bodily withdrawn from the stove, roller 58 running out of the open end of guide 59. And upon replacement of the broiler assembly within the compartment, the parts are maintained in such position that easy and quick assembly is permitted. The forward end of the guide 59 is spaced inwardly of the compartment a short distance from the ends of the track members 35, and as a result the rollers 33 for supporting the entire frame are first engaged upon their tracks 35. As the broiler structure is further moved into position within the compartment, roller 58 automatically engages directly within the guide 59, whatever the position of adjustment thereof. Similarly rollers 30 engage and support bottom plate 22. If the adjusting mechanism has been actuated to raise the inner end of guide 59, the further movement of the broiler assembly into the compartment will result in the gradual lifting of the broiler pan support up to the desired final operative position. Suitable means may be provided for yieldingly retaining the broiler assembly in its inner operative position, and in a withdrawn position providing for access to the broiler pan support.

Thus the invention provides a mechanism operable for adjusting the elevation of a broiler pan support, the mechanism being highly effective in operation and simple in construction. Adjustment of the elevation is effected by means of a control member mounted upon a stationary part of the stove, and interconnecting means for effecting adjustment in the elevation of the broiler assembly, while at the same time permitting immediate and unencumbered withdrawal of such broiler assembly from the compartment.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a stove of the character described having a broiler compartment, a food supporting frame, a carriage for supporting said frame providing for the withdrawal thereof from said compartment, means mounted on said carriage for adjusting the elevation of said food supporting mechanism throughout a range of positions, a control member positioned on a fixed wall of said compartment, and automatically detachable connections between said control member and said adjusting means for positioning said food supporting mechanism at any selected elevation.

2. In a stove of the character described and having a broiler compartment, a broiler frame received in said broiler compartment, a closure for said broiler compartment carried by said frame, means providing for the withdrawal of said broiler frame from said broiler compartment, said frame including brackets at an end opposite said closure having guiding slots formed therein, a broiler pan support having extensions received in said slots, arms pivotally connected to said support and to the broiler frame, said slots and said arms providing for movement of said pan support through a range of substantially parallel positions, a control member mounted on a fixed portion of said broiler compartment and operable from the exterior there-

of, an adjustable guide member positioned at varying elevations within said compartment by said control member, and connections between said guide member and said pan support providing for adjustably retaining said support at a desired elevation.

3. In a stove of the character described having a broiler compartment, a withdrawable broiler frame received in said broiler compartment, a broiler pan supporting member, connections supporting said member from said broiler frame and providing for varying the elevation of said member throughout a range of parallel positions, equalizing means for causing both sides of the frame to move together, an adjustable guide member mounted on a fixed portion of said broiler compartment, an external control member for controlling the position of said guide member, and interconnecting means between said guide member and said equalizing means to effect changes in the elevation of said frame in response to changes in the setting of said control member.

4. In a stove of the character described having a broiler compartment, a food supporting mechanism and means providing for the withdrawal of said food supporting mechanism from said broiler compartment, adjustable elevating means for said food supporting mechanism, a control shaft rotatably mounted on a fixed wall of said broiler compartment and projecting there-through, an external control member on the outer portion of said shaft, cam means on the interior portion of said shaft, an adjustable guide member, follower means on said guide member cooperating with said cam means to adjustably position said guide member in response to movements of said control member, and interconnecting means between said elevating means and said guide member for varying the elevation of said food supporting mechanism in response to changes in the position of said control member.

5. In a stove of the character described and having a broiler compartment, food supporting mechanism comprising a movable broiler pan supporting frame and link means limiting the movement of said frame to a range of parallel positions of varying elevation, means providing for the withdrawal of said food supporting mechanism from said broiler compartment, an inclined guide member mounted on a wall of said broiler compartment, means for varying the inclination of said guide member, and connector means on said food supporting mechanism engaging said guide member providing for adjustment of the elevation of said mechanism in accordance with the position of said guide member.

6. In a stove of the character described and having a broiler compartment, food supporting mechanism comprising a movable broiler pan supporting frame and link means limiting the movement of said frame to a range of parallel positions of varying elevation, means providing for the withdrawal of said food supporting mechanism from said broiler compartment, an adjustable guide member rotatably mounted on a wall of said broiler compartment with its axis of rotation adjacent an end of said guide member, control means for adjusting the position of said guide member, connector means on said food supporting mechanism engaging said guide member to vary the elevation of said food supporting mechanism in response to changes of position of said guide member, the end of said guide mem-

ber adjacent its axis of rotation being so positioned that said connector means is in its lowermost position when it reaches this end of said guide member during withdrawal of said food supporting mechanism.

7. A stove of the character described having an oven compartment, a broiler frame, means for supporting said frame for movement into and out of said compartment, a closure for said compartment carried with said frame, a pan support, mechanism on said frame providing for adjustably carrying said support at a desired elevation, a member adjustably attached to the wall of said compartment, means operable from the exterior of said compartment for adjusting the position of said member, and means interconnecting said member with said mechanism providing for operating said mechanism to position said pan support at a desired elevation in response to adjustments of said member.

8. A stove of the character described having a broiler compartment, a broiler pan support, means for mounting said pan support for movement into an operative position within said compartment and into a withdrawn inoperative position, said pan support also being completely removable from said compartment, means positioned upon a fixed part of said stove and interconnected with said pan support providing for adjusting the elevation of said pan support in the operative position thereof, and means providing for ready disengagement of said pan support and said adjusting means to provide for removal of said pan support from said broiler compartment.

9. A stove of the character described having an oven compartment, a broiler pan support, means for mounting said pan support for longitudinal

movement into an operative position within the compartment and into a withdrawn inoperative position, means for controlling the adjustment of the elevation of said pan support including means for adjusting the elevation of said support over a range of elevations when stationary longitudinally in operative position, and means requiring the pan support to move to a uniform elevation in withdrawn position regardless of its elevation in operative position.

10. A stove of the character described having an oven compartment, a broiler pan support, means for mounting said pan support for movement into an operative position within said compartment and into a withdrawn inoperative position, means for receiving the pan support at a predetermined uniform elevation when in withdrawn position and for effecting the lifting thereof as the pan support is moved longitudinally into its operative position, and means for adjusting the final elevation of the pan support when it reaches said operative position.

11. A stove of the character described having an oven compartment, a broiler pan support, means for mounting said pan support for movement into an operative position within said compartment and into a withdrawn inoperative position, means for receiving the pan support at a predetermined uniform elevation when in withdrawn position and for effecting the lifting thereof as the pan support is moved longitudinally into its operative position, and means for predetermineding the amount of lifting of the support which takes place during longitudinal movement of the support from inoperative to operative position.

BERTRAND B. KAHN.
